3 Claims. (Cl. 204—219)

This invention relates to an electrolytic cell, more particularly for the manufacture of chlorine and caustic alkali by electrolysis of brine using a moving mercury cathode.

It is a well-established practice to electrolyze brines in cells having a moving mercury cathode. It has hitherto been found most satisfactory to use flowing mercury cathodes which are substantially horizontal, as such an arrangement minimizes the problem of maintaining a continuous unbroken mercury surface during electrolysis. This continuity of the mercury surface is especially important in cells in which the mercury covers an iron support, since exposure of the iron to the electrolyte results in hydrogen evolution and corrosion. These horizontal cells have the disadvantage, however, of occupying an undesirably large floor area.

Attempts have been made to construct cells in which the mercury cathode film flows in a substantially vertical or steeply inclined direction since such cells have many inherent advantages, including particularly flexibility in operation and economy of floor space and mercury usage. The operating difficulties so far associated with these vertical cells have been even greater than those associated with the generally favoured horizontal cells, and these inherent advantages have not been enough to compensate for the additional disadvantages. In particular, it has been found that it is very difficult to maintain the anode-cathode spacing within the narrow range which gives satisfactory operating efficiency, because of wear and erosion of the conventional anode materials such as graphite. Consequently no overall advantage has hitherto been found for vertical cells.

I have now found, however, that the advantages of a vertically disposed cell for the electrolysis of brines can be obtained economically and reliably when the anode is made of titanium having a platinum metal coating thereon. The wear-resistant nature of platinized titanium, I find, makes it possible to assemble a vertical cell having an inter-electrode gap which can be maintained substantially uniform throughout the structure and over a period of use.

Thus according to my invention I provide an electrolytic cell for the manufacture of chlorine by electrolysis of brines, having a vertically disposed cathode support provided with a flowing mercury cathode film thereon and an adjacent, substantially parallel anode comprising titanium having a coating of a platinum metal on the surface thereof.

For the purposes of this invention, the term "vertically disposed" includes not only those arrangements in which the electrodes are strictly vertical, but also those in which the electrodes are inclined to the vertical to a minor extent. The angle of inclination to the vertical is preferably not very great, however, as the advantages of the vertical type of cell would then be lost or considerably reduced. In general, the angle of inclination should not be greater than about 30° to the vertical, though in some forms of apparatus less departure from the vertical than this can be allowed. It is important, for example, that the slope of the cathode surface should not cause difficulties in maintaining the mercury film and in particular should not cause the mercury to fall away from the supporting

2

surface. For this reason, an overhanging cathode support, if used, should usually be limited in slope to an inclination not greater than about 10° from the vertical.

The cathode support may be hollow or solid, but should be strong enough to withstand the pressures of brine and mercury employed and should preferably have a sufficient electrical conductivity for it to serve as a means for conducting the electrolyzing current to the mercury cathode. Convenient materials for this purpose are metals, especially iron or mild steel. A hollow cathode support has the advantage of allowing the mercury supply to be fed through it.

It is also very desirable that the outer surface of the cathode support should be made of a material upon which the mercury readily wets the surfaces and forms a satisfactory film, or that the outer surface of the support should be treated so as to achieve this. When the support is made of iron or steel, this effect can be secured by using mercury in which a small proportion of alkali metal is dissolved. Even a trace of sodium, for example 0.01% by weight by weight or less in the mercury will be sufficient to achieve this effect.

The mercury cathode film can be obtained by feeding a supply of mercury to the top of the cathode support and allowing it to flow down the cathode support. A weir or other distributing device may be used to spread the mercury and secure a suitably extensive and steadily flowing film. The mercury supply is most conveniently obtained by a recirculation system in which mercury which has passed through the cell is treated in conventional manner for recovery of its alkali metal content and the recovered mercury is returned to the cell.

The supply of mercury is preferably carried out by forming a pool of mercury in a suitable cavity at the top of the cathode support, and allowing the mercury to overflow from this pool down the surface of the cathode support. The mercury may be fed to the pool in any convenient manner, for example from an overhead supply pipe or by making the cathode support hollow and feeding the mercury upwards through it. It is preferred that the mercury feed should disturb the surface of the pool as little as possible so as to facilitate a smooth flow of mercury in the cathode film.

The anode structure may be made of titanium in any convenient form, provided with an operative anode surface consisting of a film of a platinum metal. The titanium may be the pure metal or an alloy. For economy of material it is preferred that the anode should be made of thin titanium sheet which may be supported as necessary by struts or other supporting members. The sheet may be pierced, slotted, expanded, or the like or may be replaced by a woven titanium wire gauze. An especially suitable material is the so-called "expanded" metal sheet which is made by cutting a large number of slots in a sheet of the metal and then stretching the sheet and, optionally, rolling the resulting metal mesh to flatten it.

The platinum metal may be deposited on the titanium surface by known techniques, for example by electrodeposition or sputtering, or by coating with a platinum-bearing paint and firing as in the ceramic industry. The particular nature of the deposit required will be determined principally by the electrical characteristics desired. The form and thickness of the platinum metal deposit, for example, may be any of those known and useful in the art, and may be for example an impervious plating or a porous layer. The platinum metal may be platinum itself, rhodium, iridium or alloys of more than one such metal, for example platinum-iridium alloys.

The shape of the electrodes (i.e. the anode and, for practical purposes, the cathode support) may be varied considerably to suit the circumstances, for example the

production capacity required or the materials available. The simplest possible form consists of one or more pairs of substantially parallel planar surfaces; this form, which may conveniently be termed a "plate form," has the advantage of being more compact than other forms and so is more economical of space.

An especially useful form is that in which one electrode surface is disposed around the other. This is done very conveniently by making the electrode surfaces of tubular form and mounting them coaxially, one within the other. The inner electrode may be solid or hollow, but in either case it presents an equivalent operative surface. The tubular electrodes may be of any convenient cross section, having straight or curved surfaces or a combination of these, as for example circular, elliptical, polygonal (for example rectangular or hexagonal) or that of a partially or completely flattened tube. This coaxial arrangement has the advantage of reducing the problem of maintaining an adequate uniformity, continuity or spread of mercury cathode film, by avoiding vertical edges on the cathode support surface. A cathode support surface having a cross-section which is free from abruptly angular portions (i.e. is substantially curved throughout) is especially useful in this respect. Tubular electrodes of substantially circular cross-section are preferred, however, as they are particularly easy to fabricate and assemble with the desired accuracy, and enable a substantially uniform inter-electrode gap and electrolyzing current distribution to be achieved. A plurality of pairs of coaxially arranged pairs of tubular electrodes can be used if desired, and these can be assembled in any convenient spatial arrangement, for example in honeycomb fashion. Appropriate electrical connections, for example by way of structural links, can be made between the various electrode surfaces. The flowing mercury cathode film may be provided on either the outer or the inner tubular surface of the pair; in the general, I prefer that this mercury film should be on the inner one in single pair assemblies and on the outer ones in multiple pair assemblies.

The anode may be continuous or pierced by holes. When the anode is in a form having holes through its thickness, the platinum metal may be deposited on the side remote from the cathode or on the side adjacent to the cathode. When on the adjacent side of the anode, the current efficiency will be greatest, but the chlorine evolved may block the inter-electrode gap sufficiently to hinder operation of the cell, particularly when the rate of brine feed is slow or the anode is not louvred in order to facilitate the escape of the chlorine. When on the remote side of the anode, the platinum metal still functions efficiently as an anode and the chlorine evolved, being already outside of the inter-electrode gap, readily escapes with the minimum interference in the operation of the cell. The titanium metal, being itself inoperative as an anode surface in the brine, does not prevent operation of the platinum metal surface as an anode even though the platinum metal is at a greater distance from the cathode than the titanium part of the structure.

When the anode is in a form having holes through its thickness, the brine can be fed at a relatively slow rate, and the chlorine gas which is evolved at the anode can be deflected away from the interelectrode gap by suitable shaping of the anode, for example by forming each aperture in the anode as a louvre. The direction of slope of the louvre which is most effective will depend upon the particular brine flow used. The configuration which is better suited to the particular rates of brine flow and gas evolution in individual cases can, however, be readily found by simple trial.

The brine for use in the cells of the present invention are essentially aqueous solutions of alkali metal chlorides, particularly sodium chloride and/or potassium chloride, optionally containing small proportions of other compounds and may be for example natural brines which may have been treated to remove undesirable constituents be-

for electrolysis, and includes recovered and/or partially used brines.

The flow of brine through the cell should be directed primarily through the vertical space defined by the anode and cathode, though it need not be confined to this space alone. When the anode is made of sheet material, free from any holes, the brine flow is preferably confined between the anode and cathode and a high brine velocity is used to prevent accumulation of chlorine in the anode-cathode space and consequent interference with the electrolysis. This form of cell is very suitable for the electrolysis of depleted (i.e. "partially spent") brines, and lends itself to an especially simple design in which a tubular cell is provided with copper bands at intervals along its length for the supply of electrolyzing current. The flow of brine may be in an upward or downward direction, though in the high-speed, confined flow cells, this is preferably downward.

Entry of brine and mercury, and removal of electrolyzed brine, amalgam and chlorine can be effected through conventional piping, separators, seals and other ancillary apparatus in conventional manner. Also, body members of the cell, other than those made of titanium, can be made of conventional materials, for example concrete, rubber-covered steel, and the like.

The anode-cathode spacing may be determined, as is conventional in the art, having regard for such factors as power consumption and the particular cell and operating conditions employed. Usually a gap of up to 10 mm. is employed.

Unlike the conventional graphite anodes which wear away quite rapidly, a platinized titanium anode does not wear sufficiently during use to make frequent adjustment necessary. When the cell of the present invention employs vertical electrodes, and especially when one of the electrodes also surrounds the other electrode completely, there is practically no opportunity for adjusting the inter-electrode gap once the cell has been assembled. Assembly can be carried out by careful measurement and calculation, but even so it is very desirable in some instances that there should be some provision for minor adjustment of an assembled cell when it is first put into service, so that the maximum operating efficiency can be secured. This problem of adjustment is especially difficult to solve for cells in which the anode and the flowing mercury cathode are substantially vertical, since any adjustment of the inter-electrode gap requires movement in a substantially horizontal direction. In a cell having horizontal electrodes, it is common for adjustment to be made by movement of the upper electrode directly away from the other by means of an adjustable support passing through the roof of the cell, but this simple technique cannot be adapted directly to vertical cells because the electrode support would then have to pass through the cell wall below the brine surface and the problems of sealing would be very considerable. Moreover, the adjustment of the gap would not be uniform over the whole operative surface of the electrodes unless flat electrodes were used.

I have also found that the desired degree of adjustment can readily be secured when the anode and cathode surfaces are made substantially parallel to each other and inclined to the vertical, and a means is provided for adjustment of the relative spacing of the two electrodes in a substantially vertical direction.

Adjustment of the relative spacing of the two electrodes in a vertical direction then results in a variation of the inter-electrode gap, the magnitude of which will depend on the angle at which the electrodes are inclined to the direction in which the electrodes are moved apart or together.

In this adjustable form of cell, I especially prefer a nested conical form in which each electrode is shaped as a frustum of a cone, and one (preferably the cathode) fits inside the other. This form has the advantages of great ease of fabrication and assembly, and uniformity

of inter-electrode gap. The means for adjustment of the relative spacing of the electrodes can be any convenient device for providing the desired degree of movement, for example a screw-actuated device, and the position at which the upper electrode support (usually the anode support) passes through the lid or cover of the cell can be sealed by any of the conventional sealing devices to ensure that undesired leakage of chlorine and/or brine electrolyte is kept as low as possible.

The invention is illustrated but not limited by the following drawings wherein FIGURE 1 represents a transverse vertical section of an electrolytic cell having concentric cylindrical anode and cathode; FIGURE 2 represents a transverse vertical section of an electrolytic cell similar to that in FIGURE 1 but in which the brine electrolyte is confined entirely between the anode and cathode during electrolysis, and which is primarily intended to utilise a high rate of flow of electrolyte through the inter-electrode gap; FIGURE 3 represents a transverse vertical section of an electrolytic cell similar to that of FIGURE 1 but having coaxially arranged anode and cathode, each being in the form of a frustum of a cone; FIGURE 4 represents a transverse vertical section of an electrolytic cell in which the cathode support is in the form of a plate interposed between two sheet anodes; and FIGURE 5 is a diagrammatic drawing, in transverse vertical section, of a multiple cell based on the various unit cells described above and particularly that of FIGURE 4. The drawings are not to scale. In FIGURE 1 the cell comprises a base plate 1 to which are secured cylindrical cathode support 2 and outer wall 3. Through the base plate 1 and within the hollow cathode support 2, an inlet pipe 4 is provided which passes upwardly to a barrier plate 5 which seals the whole of the inner cavity of the cathode support 2 near its upper end. The mercury supply 6 is fed through this inlet pipe 4, and forms a shallow pool 7 from which the mercury overflows, across the upper edge 8 of the cathode support 2 to form a thin flowing film of mercury 9 on the outer surface of the cathode support 2, and then collects in another pool 10 from which it is run off through outlet pipe 11.

Surrounding the cathode support 2 and the mercury film 9 flowing on its surface, is an anode 14 consisting of a cylinder of platinized titanium metal sheet, gauze or expanded metal sheet, held in place by current-carrying supports 13. Insulating gaskets separate these current-carrying supports 13 from the outer wall 3 and an upper wall section 15, the assembly being clamped rigidly together by threaded rods 25 and nuts 26. The upper wall section 15 is provided with a channel member 16 at its upper end, containing water 17 into which a downwardly projecting rim 18 of cover 19 dips to form a gas-tight seal. The lid or cover 19 carried a brine inlet pipe 23 and a chlorine outlet pipe 36 for the gas evolved during electrolysis. The body of the cell is filled with brine 27.

In use, the central cathode support is connected to the negative pole of the electrolyzing current supply by a suitable connecting lead (not shown) and the anode supports 13 are likewise connected to the positive pole of the electrolyzing current supply. Brine is fed in through pipe 23 in the lid 19, and then flows downwards through the cell and is electrolyzed where it passes between anode 14 and mercury film 9, and finally flows out of the cell as "spent" brine through an outer pipe 28 situated at a convenient position in outer wall 2. The mercury is fed in

through pipe 4 and is taken out of the cell through pipe 11 as a weak alkali metal amalgam, which is then treated in an apparatus (not shown) for recovery of the alkali metal content, particularly as caustic alkali, and is then fed back to the cell for re-use. Chlorine evolved during electrolysis rises through the brine in the cell and is taken off through the pipe 36.

In FIGURE 2, the apparatus shown is similar to that of FIGURE 1 except that the anode 14 is in this case an unperforated cylinder of which the upper end 14A extends above the upper lip 8 of the cathode support 2, and brine flow is confined between the anode 14 and the mercury film 9. The other parts and the mode of operation are otherwise those described for FIGURE 1.

In FIGURE 3, the anode 14 and the cathode support 2 are conical in form and the anode 14 is carried on a current-supplying support 13 which passes out through the cover 29 of the cell through a gas-tight gland 30 and is provided with a threaded rod 31 and nuts 32 by which its position can be adjusted in a vertical direction.

In FIGURES 4 and 5, the cell comprises a body 40 provided with a clamped cover 41, brine inlets 42 and 43 (these are alternatives, but can both be used if desired), a chlorine exit pipe 44, and at its lower end an exit pipe 25 and separator 45 through which amalgam and spent brine can be drawn off through pipes 46 and 47 respectively. The body 40 is filled with brine 48 and a hollow plate-shaped cathode support 49 is held in place by attachment to a clamped base plate 50. Two sheets of platinized 30 titanium (sheet or mesh) 51 are disposed on opposite sides of the cathode support and anodically connected to a source of electrolyzing current by any convenient means (not shown). Mercury is fed through a pipe 52, through the hollow centre 53 of the cathode support 49, and spills 35 out from the top of the plate and flows downwards over both sides of support 49 as a film 54 to collect at the bottom as a pool 55.

What I claim is:

1. Electrolytic cell for the manufacture of chlorine by electrolysis of brine having a vertically disposed cathode support in the form of a frustum of a cone provided with means for flowing a mercury cathode film thereon, and an adjacent, substantially parallel anode comprising titanium having a coating of a platinum metal on the surface 45 thereof.

2. Electrolytic cell as claimed in claim 1 wherein the cathode support is in the form of a right frustum of a cone.

3. Electrolytic cell as claimed in claim 1 having means 50 for relative adjustment of the electrode surfaces in a vertical direction.
